(57) **CLAIM**

I claim the ornamental design for a snap-mount safety light, as shown.

DESCRIPTION

FIG. 1 is a top perspective view of the invention

FIG. 2 is a top view of the invention

FIG. 3 is a front view of the invention

FIG. 4 is a right side view of the invention

FIG. 5 is a left side view of the invention

FIG. 6 is a bottom view of the invention; and,

FIG. 7 is an exploded side view of the invention.
